ALBERT T. HAGAMAN, OF LOUISA, KENTUCKY.

OIL-WELL EQUIPMENT.

Application filed January 29, 1923. Serial No. 615,592.

To all whom it may concern:

Be it known that I, ALBERT T. HAGAMAN, a citizen of the United States, and resident of Louisa, in the county of Lawrence and 5 State of Kentucky, have invented certain new and useful Improvements in Oil-Well Equipments, of which the following is a specification.

This invention relates to well equipment 10 and more particularly to a liquid pumping means.

Briefly stated an important object of this invention is to provide a pumping means for wells having a supplemental or reserve 15 traveling valve which is normally located in the lower portion of the working barrel and which is brought into play in the active portion of the working barrel when the main traveling valve becomes worn and unsafe 20 for efficient pumping.

A further object is to provide a pumping apparatus for wells wherein the upper or main traveling valve constitutes a sand ar- 25 rester or collector, when the supplemental or reserve traveling valve is brought into use and by reason of this construction the supplemental or reserve valve is maintained more or less free from the cutting action of sand suspended in the oil.

30 A further object is to provide a pumping equipment wherein upper and lower traveling valves are provided with separate spherical valves, each one of which is provided with a seat and by providing a plurality of 35 valves at spaced points in the line the positive lifting of the oil is provided for.

40 A further object is to provide an oil well equipment of the character specified which is of highly simplified construction, durable in use and cheap to manufacture.

Other objects and advantages will be apparent during the course of the following description.

In the accompanying drawing, forming a 45 part of this application and in which like numerals are employed to designate like parts throughout the same,

Figure 1 is a vertical sectional view 50 through a working barrel equipped with the cooperating traveling valve, the upper valve being shown in the active part of the working barrel and the lower valve being shown in the lower portion of the working barrel, the lower portion of the working barrel be- 55 ing increased slightly in internal diameter.

Figure 2 is a vertical sectional view through the working barrel equipped with the upper and lower travelling valves, the lower travelling valve being arranged in its operative position in the active portion of 60 the working barrel and the upper travelling valve being positioned to prevent settling of the sand on the lower working barrel, the view also illustrating the separate and independent ball valves for the several travel- 65 ling valves.

In the drawing wherein for the purpose of illustration is shown a preferred embodiment of my invention, the numeral 5 designates a casing within which a pumping barrel generally designated by the numeral 6 is located and by reference to Figures 1 and 2 it will be seen that the working barrel consists of an active portion 7 within which one of the travelling valves operates and the 75 lower portion of the working barrel is enlarged in internal diameter. As is well known the lower portion of the working barrel 6 is provided with a standing valve, the lower portion of which is perforated for 80 the admission of oil.

The oil is elevated in the working barrel by means of a travelling valve 10 consisting of a plurality of cup leathers 11 spaced by means of the usual bushings and the upper portion of the travelling valve 10 is provided with a cage 12 within which a one-way valve 14 of spherical formation is located. The travelling valve 10, is of course, reciprocated in the active portion 7 of the working barrel by an operating device, such as a pumping power connected to a sucker rod 15. When the sucker rod 15 and the travelling valve 10 is moved downwardly in the working barrel the oil which has been previously elevated is passed through the travelling valve and the ball valve 14 is elevated. On the subsequent upward movement of the travelling valve the oil is moved upwardly and out of the well to a suitable point of 95 discharge such as a tank.

In the pumping equipment now in use and in fact in connection with this invention the travelling valve 10 and more specifically the cup leathers 11 wear so that the working fit between the travelling valve and the working barrel is broken. In this case the travelling valve will not pump efficiently and consequently will elevate the travelling valve 10 and bring a second travelling valve 110

18 into the reduced portion 7 of the working barrel.

When the second travelling valve 18 is brought into the active portion 7 of the working barrel the oil will be efficiently pumped. Figure 1 illustrates that when the lower travelling valve 18 is in the enlarged portion 8 of the working barrel it will be out of working engagement with the wall of the working barrel. However, the ball valve 20 in the lower travelling valve is intended to operate at both positions of the travelling valve 18.

The lower travelling valve is provided with a one-way spherical valve 20 by means of which the return of the oil is prevented. On the downward movement of the travelling valve 18 when the same is its active position, the valve 20 is elevated and the oil will flow through the travelling valve 18 and a tube 22, the said tube serving to rigidly connect the upper and lower valves. It will be seen that the lower portion of the connecting and oil conducting tube 22 is provided with a series of inwardly projecting lugs or retaining devices 23 by means of which the upward movement of the valve 20 is limited. However, the inwardly projecting lugs 23 do not in any way interfere with the passage of oil through the tube 22.

In operation the sucker rod 15 is reciprocated and the upper travelling valve 10 is arranged in the active portion 7 of the working barrel while the lower travelling valve 35 is arranged in the inactive portion 8 of the working barrel. When the cup leathers 11 become worn as a result of sand suspended in the oil the well will not operate efficiently and it is then that the lower travelling valve 40 18 is brought into operation by elevating the sucker rod 15.

When the lower travelling valve 18 is brought into use the cup leathers 11 which are not worn constitute sand arresters and therefore prevent the sand suspended in the oil from settling on the cup leathers of the lower travelling valve. It might be stated that it is only the upper cup leathers 11 of the upper travelling valve which wear and the lower cup leathers 11 of the upper travelling valve then prevent the settling of the sand on the cup leathers of the lower travelling valve.

On the downward movement of the sucker rod 22 the oil is passed through the travelling valve 18 and into the connecting tube 22 and on the subsequent upward movement of the sucker rod the oil is elevated. Of course, that oil contained in the tube 22 passes upwardly through the working barrel 10 and the valve cage 12 and then upwardly through the tubing. It will be seen that the ball valves 14 and 20 coact to prevent the return of the oil which has been

pumped and therefore should one of the valves be rendered inactive for any reason the other valve will continue to function thereby enabling the well to continue to produce.

With reference to the foregoing description taken in connection with the accompanying drawing it will be seen that the upper travelling valve 10 not only forms a means for pumping the oil but also constitutes a sand arrester by means of which the said is prevented from settling on the cup leathers of the lower travelling valve and by reason of this construction the life of the lower travelling valve is greatly prolonged and the necessity of frequently pulling the travelling valve is overcome.

In summarizing it will be seen that the upper or main travelling valve is originally arranged in the active portion of the working barrel and when the same becomes worn the lower or supplemental working or travelling valve is elevated into the active portion of the working barrel. When the supplemental working or travelling valve is elevated to its operative position the main travelling valve will act as an arrester by means of which the sand is prevented from collecting on the supplemental travelling valve.

It is to be understood that the form of the invention herewith shown and described is to be taken as a preferred example of the same and what such minor changes in arrangement and construction of parts may be made as will remain within the spirit of the invention and the scope of what is claimed.

Having thus described the invention, what is claimed is:—

1. An oil well equipment comprising a working barrel having active and inactive portions, main and supplemental travelling valves arranged in the working barrel, the main travelling valve constituting a sand arrester by means of which sand is prevented from settling on the supplemental valve. 105

2. An oil well equipment comprising a working barrel having active and inactive portions, a main travelling valve arranged at all times in the active portion of the working barrel, and a supplemental travelling valve normally arranged in the inactive portion and adapted to be elevated into the active portion, the main travelling valve being adapted to maintain the supplemental travelling valve free of sand when active. 115

3. An oil well equipment comprising a working barrel having active and inactive portions, a main travelling valve arranged in the active portion of the working barrel, a supplemental travelling valve positioned beneath the main travelling valve and normally arranged in the inactive portion and adapted to be elevated into the active por- 125

tion, the main travelling valve being adapted to remain in the active portion of the working barrel and to form a sand arrester for the supplemental travelling valve, and a tubular member connecting the main and supplemental travelling valves constituting an oil conduit establishing communication

between the first and second named travelling valves.

4. The construction set forth in claim 3, and separate one-way valves for each of the said travelling valves.

ALBERT T. HAGAMAN.
